CLOSURE DEVICE

Harry S. Pletcher, Joliet, Ill., assignor to The
Moore Corporation, Joliet, Ill., a corporation of
Illinois

Application August 30, 1934, Serial No. 742,104

4 Claims. (Cl. 98—101)

This invention relates in general to closure devices, and is particularly adapted for use in circulating heaters generally employed for heating dwellings or apartments where coal or gas is used as a heating medium. In this type of heater certain disadvantages have manifested themselves causing considerable trouble to the manufacturer and discomfort to the user.

In order to gain maximum efficiency in the circulating type of heater an air tight construction was employed both in the fuel door and in the ash pit door. While this expedient accomplished the desired result, certain disadvantages were presented. It was found that the heat units surrounding the fire pot and within the confines of the heater structure, tended to warp, crack or place undue strain upon the front portion of the stove. This defect has been eliminated in the present construction which has the manifold purpose of augmenting the high efficiency in the distribution of heat units and eliminating the aforementioned disadvantages.

A principal object of the present invention is the provision of a hinged closure member and novel means for moving it to and maintain it in a desired open position.

Another important object of the invention is the provision in a circulating heater of a hinged door member placed intermediate the fuel door and ash pit door, which will normally seal the escape of heat units surrounding the fire pot and which may be swung about a common axis through novel and simple means to effect a plurality of desired positions for the escape of said heat units.

A further important object of the invention is the provision in a heater of the character described, of a freely swinging door or closure member, readily and easily operable to effect a plurality of fixed positions of said closure with a plurality of corresponding angular deflections of the heat units within said heater.

Another object of the invention is the provision of a closure device which is strong, durable, efficient, and inexpensive to manufacture.

Numerous other objects and advantages of the invention will be apparent as it is better understood from the following description, which, when taken in connection with the accompanying drawing, discloses a preferred embodiment thereof.

On the drawing,

Figure 1 is a front elevational view of a circulating heater in which the invention is embodied;

Fig. 2 is a side elevational view of a circulating heater;

Fig. 3 is a section taken substantially on the line 3—3 of Fig. 1 and shows the deflector door in closed position;

Fig. 4 is a view similar to Fig. 3 and showing the deflector door in open position;

Fig. 5 is a section taken substantially on the line 5—5 of Fig. 3 and showing the various positions of deflections which may be obtained;

Fig. 6 is a section taken substantially on the line 6—6 of Fig. 3; and

Fig. 7 is an enlarged detail view of a portion of the deflector door and operating handle within the cam member.

Referring to the drawing, reference character 11 indicates, generally, a heater composed of a front panel member 12, rear panel member 13, side panel members 14 and 15, respectively, and a top grating member 16 provided for the escape of the heat. Suitably disposed within the heater 11 are a fire pot 17, a dome shaped combustion chamber 18, and an ash pit 19.

A windowed fuel door 21 is in registration with the combustion chamber 18 and an ash pit door 22 is in registration with the ash pit chamber, these two doors being hinged to the front panel member 12 in any suitable or preferred manner.

Intermediate the fuel door and the ash pit door the front panel 12 is provided with an opening 24, substantially rectangular in form, having at its upper edge a pair of arcuate recessed portions 25 provided with openings 26, each adapted to receive a lug 27 formed integral with a deflector door or closure member 28. The closure member 28 is shown as applied to the heater 11 merely as illustrative of one of many uses for which it is adapted. The lugs 27 are provided with openings 29 through which cotter pins 31 are inserted and bent over. This construction constitutes a hinge for the deflector door, which is simple, efficient and inexpensive to manufacture and assemble.

Centrally located on the deflector door and intermediate the lugs 27, an operating handle 32 is provided having a stem 33, one end of which is suitably fastened to the handle and the opposite end 34 is bent at right angles to the stem 33. The horizontal axis of the handle and the bent end 34 of the stem (viewing Fig. 6) is adapted to lie below the axis passing through the cotter pins which constitute hinges for the deflector door (just described) and lies within an opening in an irregular shaped member 36 formed integral with the front panel member 12.

This irregularly shaped member 36 constitutes a cam for swinging the deflector door about its hinges to the various selected positions, and comprises a vertical portion 37 (Fig. 6) which merges 5 into an eccentric camming portion 38 terminating at 39 and continues with a recessed portion 41 concentric with the axis of the operating handle and beyond the arc of travel of the end of the bent portion 34 of the stem 33.

10 Viewing Figs. 3 and 4, the eccentric portion 38 slopes inwardly as at 40 towards the stem 33 so that as the stem is rotated in a clockwise direction the end of the stem will be cammed outwardly until it rests in the position shown in 15 Fig. 4.

It will be apparent that camming the stem in this manner will constrain the deflector door to swing about its hinges into the position shown in Figs. 4, 5 and 7.

20 Referring to Figs. 3 and 6, it will be seen that as the door handle is rotated clockwise the stem enters the camming portion 38 riding upon it until it reaches any of the positions shown in Fig. 5 and in rotating further will pass the extremity 39 of the eccentric portion 38, allowing 25 the deflector door to fall back into the position shown in Fig. 3. Further movement will then cause the bent end 34 of the stem 33 to contact the rear surface of the member 36 thus holding 30 the deflector door in its closed position. It will be manifest that the deflector door will maintain any of the assumed positions, as shown in Fig. 5, since the weight of the door will tend to hold 35 the stem against the camming portion 38.

35 It will be apparent that in thus deflecting heat downwardly in this manner the cold air at the base of the heater will be preheated and in this manner greatly add to the efficiency of the heater by maintaining a more uniform and evenly 40 distributed heat throughout the room.

45 It is thought that the invention and many of its attendant advantages will be understood from the foregoing description, and it will be apparent that various changes may be made in the form, construction and arrangements of the parts without departing from the spirit and scope of the invention or sacrificing all of its material advantages, the form hereinbefore described being merely a preferred embodiment thereof.

50 I claim:

1. A closure device for an opening in a wall,

comprising a cover plate for the opening, means for supporting the cover plate to constrain said plate to assume a closing position in respect to said opening, a boss projecting from the wall inward and having an inner edge spaced differentially at different points of the length of the wall in respect to the plane of the wall, and a rotatable element on the cover plate in engagement with the edge of the boss in the wall. 5

2. A closure device for an opening in a wall, 10 comprising a cover plate, means adjacent the upper edge of the cover plate for pivotally supporting said cover plate and constraining said plate to assume a closing position in respect to said opening, a boss projecting from the wall of the heater inward and having a cam edge spaced differentially at different points of its length with respect to the plane of the wall, a rotatable element extending through the cover plate, and an arm on said rotatable element in 15 permanent frictional engagement with said edge, whereby upon rotation of said rotatable element a differential spacing of the lower edge of said cover plate in respect to the opening in the wall is produced. 20

3. A closure device for an opening in a wall, 25 comprising a cover plate mounted on said wall so as to normally close said opening, and a member rotatably mounted in said cover plate and co-operating with a portion of said wall and adapted upon rotation in one direction to move said cover plate to selective open positions, and upon further rotation in the same direction to allow said cover plate to return to normal closed position. 30

4. A closure device for an opening in a wall, 35 comprising a cover plate mounted on said wall so as to normally close said opening, and a member rotatably mounted in said cover plate and co-operating with a portion of said wall for normally locking said cover plate in closed position, and adapted upon rotation in one direction to move said cover plate to selective open positions and maintain said plate in any of said selective positions, and adapted upon further rotation in the same direction to allow said cover plate to return to normal closed position, and upon further similar rotation to again lock said cover plate in closed position. 40 45
